SUPPORTING DEVICE

John C. Bridges, Dallas, Tex., assignor to
Ellen C. Eiselein, Dallas, Tex.

Application May 9, 1946, Serial No. 668,599

9 Claims. (Cl. 248—279)

1

This invention relates to new and useful improvements in supporting devices, and particularly to such devices adapted for use with hospital beds for supporting articles such as irrigation cans, containers of plasma, glucose, and the like.

One object of the invention is to provide an improved supporting device which is adjustable to various positions for supporting medical accessories in proper and convenient elevated positions for use by, or in treatment of, a patient confined in a bed.

An important object of the invention is to provide an appliance of the character described which is adapted to be secured to the head or foot frame member of a bed in a manner which permits it to be adjustably positioned at various points over the bed or at the side thereof for supporting medical accessories used in the treatment of patients in said bed.

Another object of the invention is to provide a supporting device of the character described which is arranged to be retractable, when not in use, to a position which does not interfere with the normal use of the bed.

A particular object of the invention is to provide a supporting device of the character described having an improved means for maintaining such supporting device in various adjusted positions with respect to the bed on which it is mounted or secured, being swingable above and away from the bed when in elevated position.

A further object of the invention is to provide a device of the character described which is adapted to be normally maintained in an inoperative or retracted position in which it will not interfere with the normal use of the bed to which it is secured, and which may readily be adjusted to supporting position ready for use when desired.

Still another object of the invention is to provide an appliance of the character described which does not have detachable parts and is constantly maintained in condition ready for use.

Additional objects and advantages of the invention will readily be apparent from a reading of the following description of a device constructed in accordance with the invention, and reference to the accompanying drawings thereof, wherein:

Figure 1 is a view, in elevation, showing a supporting device attached to a bed and in elevated position ready for use;

2

Figure 2 is an enlarged view, in elevation, showing the device in inoperative or retracted position.

Figure 3 is an enlarged fragmentary view, in elevation, more clearly illustrating the manner in which the supporting arm is adjustably secured in elevated position on the base member.

Figure 4 is an enlarged fragmentary plan view of the base member and lower end of the supporting arm.

Figure 5 is an enlarged cross-sectional view taken on the line 5—5 of Figure 1, and

Figure 6 is an enlarged end view taken along the line 6—6 of Figure 2.

In the drawings, a bed B, having the customary vertical head or foot frame member 10, is illustrated as having the support S of the invention secured thereto. The support includes a substantially rectangular plate or base member 11 which is secured by means of substantially U-shaped clamping straps 12 to one upright of the vertical frame member of the bed. The straps 12 have their ends threaded for receiving nuts 13, whereby the base member may be fixed securely on the frame member 10, as clearly shown in Figure 1.

Extending vertically to the face of the base member at its upper end is a horizontal pivot plate or turntable 14 having an opening 15 therethrough for receiving one end of an elongate pivot or hinge pin 16. The pin is held securely so as to be pivoted on the plate 14 by a retaining washer or member 17 retained on the end of the pin below the pivot plate by means of a cotter pin or key, as clearly shown in Figures 2 and 3. The hinge pin is bent at a right angle just above the upper surface of the pivot plate and extends substantially beyond the edge of such pivot plate, whereby an elongate supporting arm or rod 19, preferably tubular, may be secured on such hinge pin by means of a transverse opening formed in such rod near one end thereof. The rod is retained on the hinge pin by means of a ring or washer 23 securely held on the extreme outer end of such hinge pin by a cotter pin or key, and may be swung in an arc upon the hinge pin.

The supporting rod 19 is provided with a substantially flat end portion 21 adjacent the hinge pin, and a longitudinally extending slot 22 is formed centrally of such flattened portion 21, for a purpose which will hereinafter be explained. Obviously, this flattened portion of the rod or arm

19 may be formed by actually flattening the tubular rod by pressing the walls thereof together, or it may be formed on one end of a bar of solid round material which has its remaining round portion inserted within the tubular rod 19 and secured therein by welding or otherwise. In the latter case, the solid bar will extend past the opening through which the hinge pin 16 extends, and thus will provide additional support for such supporting arm and hinge pin.

An elongate inverted J-shaped hook or catch member 24 has its lower end extending through an opening formed in a horizontal flange 25 provided at the lower end of the base member in vertical alignment with the opening 15 in the pivot plate. The opening in the flange is large enough to permit the catch member 24 to swing in an arc therein to various positions below the pivot plate 14, as shown in Figures 1, 3 and 4. A bearing ring or washer 26 is loosely confined on the extreme lower end of the catch member by means of a pin or cotter key, or other suitable means, to prevent upward displacement of the catch member from within the opening through the flange 25. A stop ring or member 27 located substantially centrally of the catch member limits downward movement of such catch member with respect to the flange.

The upper end of the catch member is bent upon itself to form a hook having a short off-set portion or arm 28 extending substantially parallel to the longer arm or body portion of said catch member, and it is preferable that this off-set portion or arm be somewhat longer than the diameter of the material from which the catch member is made, but short enough to permit such off-set portion or arm 28 to pass through the slot 22 formed in the elongate supporting rod 19 when inserted therethrough parallel to the longitudinal dimension of such slot. However, since the length of the off-set portion or arm 28 is greater than the diameter of the catch member, it is obvious that when the arm 19 is turned so that the slot 22 is disposed at an angle to such off-set portion 28, the off-set portion cannot be withdrawn through the slot, and the catch member is positively but loosely connected to the end of the supporting rod 19, as clearly shown in Figures 1 and 3.

It will be seen therefore, that the rod 19 will be maintained in the elevated position shown in Figure 1 when the hook or catch member 24 is engaged in the slot 22 at the end of such rod, the engagement of the bearing washer 26 at the lower end of the catch member with the under side of the flange 25 preventing further upward movement of the catch member and positioning the elongate supporting rod 19 in operative position.

Obviously, the angle at which the rod 19 is held may be varied by varying the length of the hook or catch member 24, or by adjusting the position of the bearing member 26 on such catch member to increase or decrease the effective length of such catch member.

Since the hinge pin 16 is swingable through an arc in a horizontal plane on the upper surface of the turntable or pivot plate 14 it will readily be seen that the hinge pin may be turned or swung through a range of positions to swing the elongate supporting rod 19 inwardly over the bed or outwardly at an angle therefrom. It will further be seen that, since the catch member is loosely retained at its lower end in the flange 25, the upper end of said catch member may also swing

5 to permit such movement of the elongate supporting rod or arm. The long horizontal portion of the hinge pin 16 will ride or slide along the upper surface of the turntable or pivot plate 14 and will be amply supported thereby to provide a rigid support for the elongate supporting arm.

When not in use, the catch member 24 is disengaged from within the slot 22 at the end of the elongate supporting arm 19 and said arm is permitted to swing downwardly to the position illustrated in Figure 2, where it will lie parallel to the vertical head or foot frame member 18 and not interfere with normal use of the bed. However, the supporting arm may again readily be raised 10 to operative position by swinging the same upwardly, pivoting about the hinge 16, until the slot 22 in the flattened end of such arm is in position to receive the off-set hook arm 28 of the catch member, whereby the catch member is engaged within the slot and the arm is positively held in elevated operative position.

An elongate extension arm or bar 30, which is preferably tubular for strength and to reduce weight, is slidable through the lower half of an oval saddle or guide member 31, the upper half of which is fixed to the outer end of the supporting rod or arm 19, as clearly shown in Figure 1. A slide or rider member 32 is secured to the inner end of the extension bar 30 and has clamping arms 33 engaging around the supporting rod 19, as best shown in Figure 5. A clamping bolt 34 extends transversely of the clamping rider 32 through a notch formed in the extension bar and has a wing nut 35 threaded thereon for 25 clamping the arms 33 tightly about the supporting rod 19, whereby the extension arm may be adjustably secured at various extended positions by clamping the rider 32 at various points along the supporting rod. The end of the bolt 34 is bradded to prevent loss of the wing nut.

The length of the extension bar 30 is such that, when fully retracted as shown in Figure 2 the clamping rider 32 will be positioned adjacent the hinge pin 16 and may be clamped in such position to securely hold the extension bar so retracted. Manifestly, other means of securing the extension bar in adjusted extended elevated position may be provided, but the means illustrated is preferable.

50 An elongate hanger member 40 is pivotally secured at one end to a clamp or strap 41 affixed to the outer end of the extension bar 30. The hanger is adapted to be turned to a position parallel to the extension bar and to enter the bore 55 of the tubular supporting rod 19 when the extension bar is moved to retracted position, as shown in Figures 2 and 6, whereby it is protected by and held in inoperative position within said supporting rod. In use, the hanger member is swung 60 outwardly about the pivot to the position illustrated in Figure 1, wherein it is supported within a slot at the outer end of the extension bar and at an angle slightly below the horizontal. A plurality of hook-like recesses 42 are formed at spaced 65 intervals in the upper edge of said hanger member and are adapted to receive the bails or other supporting elements (not shown) of the medical accessories which are to be supported by or hung from the supporting device.

70 An open supporting ring 45 has radially extending arm 46 which are pivoted to a supporting strap 47 affixed to the outer end of the extension bar by means of a clamp 48 surrounding said bar adjacent the clamp strap 41. The ring is held in 75 substantially a horizontal position, as illustrated

in Figure 1, by means of a supporting pin 49 which is inserted through a hole provided in the strap 47 at an angle of approximately 45 degrees below the pivot by which the ring member is attached to said strap. The pin 49 engages the edges of the arms 46, whereby the ring may be supported in the position illustrated in full lines in Figure 1 for use, or, may be turned to the position illustrated in dotted lines when not in use, and is positively held or maintained in such positions by said pin.

From the foregoing, it will be seen that the supporting device may be attached to either the head frame or the foot frame of the bed and that the supporting arm 48 may readily be swung into position with the catch member 24 engaged in the slot 22, and the extension bar 30 may be moved to an extended elevated position such as is shown in Figure 1, whereupon the supporting device is ready for immediate use. It will further particularly be seen that the supporting device may be swung inwardly over the bed or outwardly therefrom as desired, to facilitate handling or treatment of the patient in the bed.

Also, the angle and height to which the supporting rod and the extension bar are adjusted may be varied by varying the effective length of the catch member 24 in such a manner that the hanger member may be so positioned as to properly locate the medical accessories at the desired point over the bed for use in treatment of the patient confined therein.

It is particularly to be noted that the catch member 24 is locked in the slot 22 in the supporting rod when the arm is positioned for use, as shown in Figures 1, 3 and 4, and cannot readily be disconnected therefrom until the supporting rod is swung to a substantially vertical position to permit the withdrawal of the off-set portion or arm 28 of the hook or catch member from within the slot.

Furthermore, the tubular supporting rod and extension bar, the hanger member, and the supporting ring are all arranged to be retracted into a compact unit when not in use, and that the extension bar may be securely clamped to the supporting rod in such retracted position, as shown in Figure 2. It will also be seen that the support is constantly ready for use, even when conveniently stored in a retracted position in which it will not interfere with the normal use of the bed, and may readily be raised from such position to operative position when needed.

The foregoing description of the invention is explanatory only, and changes in the details of the construction illustrated may be made by those skilled in the art, within the scope of the appended claims, without departing from the spirit of the invention.

What I claim and desire to secure by Letters Patent is:

1. A supporting device including, a base member, a pivot plate carried by said base member, a hinge member swingably mounted on and supported by the upper surface of the pivot plate and projecting beyond the edge of said plate, an elongate supporting arm swingably secured on the projecting end of the hinge member, and adjustable means mounted on the base member and engageable with the supporting arm for swingably maintaining said arm in an elevated position.

2. A supporting device of the character set forth in claim 1 wherein the means engageable with the supporting arm for swingably maintaining said

arm in an elevated position is releasable from said arm to permit retraction of said supporting arm from such elevated position.

3. A supporting device including, a base member having a pivot plate at its upper end, a hinge member pivotally secured to the pivot plate and supported upon and swingable horizontally thereabove and projecting beyond the edge thereof, an elongate supporting arm pivoted at one end on the projecting portion of said hinge member so as to be swingable on said hinge member about the axis of said member, said arm also being swingable with said hinge member as the same is swung in a horizontal plane, and movable catch means mounted on the base member below the pivot plate engageable with the shorter portion of the supporting arm for maintaining said arm in a movable elevated position.

4. A supporting device including, a base member, a pivot plate on said base member and adapted to lie in a horizontal plane, a hinge member mounted on and projecting beyond the edge of said pivot plate and adapted to swing thereon in a horizontal plane and be supported thereby, an elongate supporting arm pivotally secured near one end upon the projecting portion of said hinge member and adapted to swing with said hinge member, movable catch means mounted on said base member engageable with the shorter portion of the supporting arm for maintaining said arm in an elevated position, and means normally preventing disengagement of said catch member from said arm.

5. A supporting device including, a base member adapted to be secured in an upright position on a vertical section of a bed frame, a pivot plate carried by said base member and adapted to lie in a horizontal plane, a hinge member pivotally mounted on said pivot plate and projecting beyond said plate and being supported on and swingable thereabove in a horizontal plane, a supporting arm pivotally mounted on the projecting end of the hinge member and adapted to swing with said hinge member as the same is moved in a horizontal plane, said supporting arm also being swingable on said hinge member about the longitudinal axis thereof, and an elongate catch member loosely connected at one end with the base member and having a hook member at its other end engageable with the supporting arm for maintaining said arm in a movable elevated position.

6. A supporting device including, a base member adapted to be secured in an upright position on a vertical section of a bed frame, a pivot plate carried by said base member and adapted to lie in a horizontal plane, a hinge member pivotally mounted on said pivot plate projecting beyond said pivot plate and supported upon and swingable thereabove in a horizontal plane, a supporting arm pivotally mounted on the projecting end of said hinge member so as to be swingable thereon about the longitudinal axis thereof and adapted to swing with said hinge member as the same is moved in a horizontal plane; an elongate catch member loosely and swingably connected at one end with the base member and having a hook member at its other end engageable with the supporting arm for maintaining said arm in an elevated position, and means normally preventing disengagement of said hook member from said supporting arm, said last-named means being releasable whereby the supporting arm may be swung upon the hinge member from elevated to retracted position.

7. A supporting device including, a base member adapted to be secured in an upright position on a bed frame, a pivot table carried by the base member, a hinge pin pivotally secured at one end on the pivot table and having its other end projecting beyond the pivot table and swingable in a horizontal plane above said pivot table so as to be supported thereby, a supporting arm swingably mounted near one end upon the projecting swingable end of the hinge pin so as to be swingable thereon about its longitudinal axis and to be swingable with said hinge pin as the same is moved in a horizontal plane, said supporting arm having an elongate slot at one end of its shorter portion, and a catch member having one end loosely and swingably connected with the base member and having a hook member at its other end adapted to engage within the slot in the supporting arm when in alignment therewith, said hook member being normally prevented from disengagement from within said slot when not in alignment therewith.

8. A supporting device including, a base member, a pivot plate carried by the base member, a hinge member swingably mounted on said pivot plate and having its outer end projecting beyond the edge of the pivot plate, an elongate supporting arm pivotally secured near one end on the projecting outer end of the hinge member and swingable about the axis of said hinge member, means mounted on the base member and engageable with the shorter portion of the supporting arm for swingably maintaining the longer portion of said arm in an elevated position, and an extension bar carried by the longer portion of the sup-

porting arm and adjustable longitudinally with respect to said arm.

9. A supporting device including, a base member, a pivot plate carried by the base member, a hinge member swingably mounted on and supported by said pivot plate and having its outer end projecting beyond the edge of the pivot plate, an elongate supporting arm pivotally secured near one end on the projecting outer end of the hinge member and swingable about the longitudinal axis of said hinge member, means mounted on the base member and engageable with the shorter portion of the supporting arm for swingably maintaining the longer portion of said arm in an elevated position, and extension bar mounted adjacent and parallel to the longer portion of supporting arm, means at one end of each the arm and bar engaging around the other to guide the extension bar in its longitudinal movement with respect to the supporting arm, and means for preventing movement of such extension bar with respect to the supporting arm, said means being releasable and adjustable.
